Patented Apr. 11, 1967

207,394

SHOE SHINE MACHINE

William F. Kelly, Rte. 2, Cleburne, Tex. 76031

Filed Sept. 19, 1966, Ser. No. 3,910

Term of patent 14 years

(Cl. D9—2)

Fig. 1

Fig. 2

Fig. 3

FIG. 1 is a perspective view of a shoe shine machine embodying my new design;

FIG. 2 is a front elevational view thereof; and

FIG. 3 is a side elevational view thereof taken from the right of FIG. 1.

The side not shown has substantially the same appearance as the side shown.

I claim:

The ornamental design for a shoe shine machine, as shown and described.
